(57) **CLAIM**

The ornamental design for a carton, as shown and described.

DESCRIPTION

FIG. 1 is a perspective view of a carton according to the disclosure.

FIG. 2 is a left elevation view of the carton of FIG. 1, the right elevation view being identical.

FIG. 3 is a front elevation view of the carton of FIG. 1, the rear elevation view being identical; and,

FIG. 4 is a top plan view of the carton of FIG. 1, the bottom plan view being a mirror image.

The bold dash-dot-dot lines shown adjacent the shaded regions show the boundaries of the claimed subject matter.

All evenly-spaced broken lines depict environmental subject matter only that forms no part of the claimed design and form no part thereof.
